Des. 221,971
Patented Sept. 21, 1971

221,971

FLOWER URN

Charles J. Terrell, 740 Van Deman St.,
Washington Court House, Ohio 43160

Filed Sept. 3, 1970, Ser. No. 24,827

Term of patent 14 years

Int. Cl. D11—02

U.S. Cl. D35—3

FIG. 1

FIG. 2

FIG. 3

FIG. 4

FIG. 5

FIG. 8

FIG. 6

FIG. 9

FIG. 7

FIG. 1 is a perspective view of a flower urn showing my new design;

FIG. 2 is a top plan view thereof;

FIG. 3 is a side elevational view thereof; and

FIG. 4 is a bottom plan view thereof;

FIG. 5 is a perspective view of a second embodiment of a flower urn showing my new design;

FIG. 6 is a top plan view thereof;

FIG. 7 is a front elevational view thereof;

FIG. 8 is an end elevational view thereof; and

FIG. 9 is a bottom plan view thereof.

I claim:

The ornamental design for a flower urn, as shown and described.
